UNITED STATES PATENT OFFICE.

FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

FEED MECHANISM FOR SEWING-MACHINES.

No. 923,062.

Specification of Letters Patent.

Patented May 25, 1909.

Application filed October 30, 1905. Serial No. 284,941.

To all whom it may concern:

Be it known that I, FRANK W. MERRICK, a citizen of the United States, residing at Boston, in the county of Suffolk, State of 5 Massachusetts, have invented a certain new and useful Improvement in Feed Mechanisms for Sewing Machines, &c., of which the following is a specification, reference being had therein to the accompanying drawings.

10 The invention has relation to feed-mechanisms on the order of those which are employed in hook-needle wax-thread sewing machines, and consists, generally, in a feed-mechanism of such order of novel and improved construction, which, while more especially designed for use in a sewing machine, is equally applicable to other machines in which the material or stock operated upon is both pierced and fed.

20 In a feed-mechanism embodying the invention the feed-post has combined therewith an arm mounted to vibrate around a fixed center, a link having one end thereof in pivotal connection with the said arm, the 25 other end of such link having operative connection with the feed-post, and an actuating cam for the said arm. The arm and link are combined and arranged in proper relative position to act in the manner of a toggle 30 or toggle-joint, and the actuating cam acts to effect the operation of the feed-post by producing movement of the knuckle or joint, produced by linking together the arm and link, in directions which extend trans-

35 versely with respect to the line joining the center about which the arm swings with that at the outer end of the link. Thus, as the knuckle or joint of the toggle is moved by the action of the cam in the direction 40 toward the said line, a movement in one direction along the line of feed is transmitted to the feed-post; as the knuckle or joint is moved in the reverse direction, that is, away from the said line, a movement of the 45 feed-post in the opposite direction is occasioned.

An embodiment of the invention in a needle-feed mechanism for sewing machines is illustrated in the drawings, in which 50 latter,—

Figure 1 shows in front elevation part of a sewing machine containing the said embodiment. Fig. 2 is an end elevation looking from the left-hand side of Fig. 1. 55 Fig. 3 is a view resembling Fig. 2, but with

portions broken away or in section in order to show parts which otherwise would be hidden. Fig. 4 is a detail view on an enlarged scale, partly in section, showing the connection between link 25 and arm 200 60 of the rocker 20.

Having reference to the drawings,—at 1 is the base of the fixed frame of a sewing machine, at 2 the work-post rising from the left-hand end of the said base in Fig. 1, and at 3 65 is a work-support that is carried by the top of the said work-post, a portion of the upright part of the frame at the right-hand end of the same being shown at 4, and a portion of the head of the machine being shown at 5. 70

At 6 is the presser above the work-support, and at 7 the presser-bar to which the presser is secured, the said presser-bar being mounted in head 5, as usual.

At 8 is a hook-needle working from below, 75 at 9 the needle-bar, carrying the said needle and located below the work-support, and at 10 the feed-post. The said feed-post is provided with guides to which the needle-bar is fitted and within which it is reciprocated 80 lengthwise by operating connections comprising a link 11 having the upper end thereof pivotally joined to the needle-bar and its lower end connected to a crank-pin 12 which is carried by a disk 13 fast upon a rotating 85 horizontal shaft 14. The said shaft is mounted in bearings at 15, 15, Fig. 1, which are supported in the base 1 of the frame of the machine.

At 16, Fig. 1, is a miter-gear fast upon the 90 shaft 14, and at 17 is a like gear meshing with gear 16 and fast upon an upright shaft 18 which is mounted in bearings in the upright portion 4 of the frame, one of said bearings being shown at 19. The upright shaft 18 95 is in practice driven through suitable motion-transmitting connections (not shown) at its upper end from the driving-shaft of the machine (also not shown) and transmits rotary motion to horizontal shaft 14 through 100 the miter-gears 16, 17.

As thus far described, the parts are not of the gist of the invention.

The feed-post 10 is supported by a pair of parallel rockers 20, 21, on the order of those 105 of United States Letters Patent for feed mechanism for sewing machines granted to me under date of April 11, 1905, No. 786,909, operating on the principle of parallel links to keep the needle-bar parallel with the path 110

of its endwise movements at all times during the feed-movements. The respective rockers are located at opposite sides of the shaft 14, the rocker 20 being at the front of the 5 said shaft in Fig. 1, and the rocker 21 being at the rear thereof.

At 22, 22, etc., are center-screws, carried by the opposite ends of the base 1 of the fixed frame of the machine, engaging with the opposite ends of the respective rockers 20, 21, 10 and which serve to support the latter.

At 200, 210, respectively, are the upwardly-extending arms of the respective rockers, to which arms the feed-post 10 is connected pivotally by the studs 201, 211, which project from one side of the feed-post at the front and rear, respectively, of the work-post 2. In the present instance, each of the said arms is of considerable width and is furnished at its 20 upper end with a sleeve-like portion of considerable length which receives within the same the corresponding stud, as shown best in Fig. 1.

At 202, 203, Fig. 1, are bearing-cones with 25 which each stud projecting from the feed-post is provided, such bearing-cones facing each other, and being located at or adjacent the opposite ends of the stud. They work in corresponding tapering portions of the bore 30 of the sleeve which is occupied by such stud. The cone 202 next adjacent the feed-post is integral with the body of the stud. That, 203, at the free end of the stud is formed in a separate piece, and is internally screw-threaded to fit the correspondingly threaded exterior of the stud. It is screwed upon the latter into proper bearing-contact with the adjacent tapering bearing-surface of the sleeve, it being adjustable upon the screw-threaded portion of the stud to enable play 35 and wear to be taken up, and is provided with a lock-nut, 204, to prevent accidental loss of adjustment.

The devices operating to cause the feed- 40 movements of the feed-post comprise a feed-cam which is fast upon the shaft 14, a vibrator which is pivotally mounted in connection with the fixed machine-frame, and a link connecting the said vibrator with one of the 45 rockers. Movement imparted to the vibrator by the cam in rotating is transmitted through the link to the rockers and feed-post. The parts just referred to are shown best in Fig. 3. In the drawings the feed-cam 23 is 50 a so-called triangular-cam or "eccentric". The vibrator consists of a rock-shaft 241 and an arm 24. The said rock-shaft is mounted at its ends upon center-screws 2421, one of which is shown in Fig. 2, that are applied to 55 opposite ends of the fixed frame 1. The said arm is connected with the rock-shaft. The pivotal axis of the vibrator is located at one side of the shaft 14, namely at the rear or left-hand side thereof in Figs. 2 and 3. 60 The arm 24 extends from the said pivotal 65

axis toward the opposite side of the said shaft, namely toward the front or right-hand side in Figs. 2 and 3, and the link 25 extends from the said arm in the same general direction and connects with the rocker 20 at the front 70 of the shaft 14. The arm 24 is forked and the two members of the fork receive between them the cam 23, the edge of which latter makes contact with the inner surfaces of the 75 said members.

To provide for adjustment of the members toward and from each other the arm is split lengthwise from the inner end of the opening of the fork toward the hub-portion of the arm, as shown in Fig. 3, a screw 242 80 being passed through the opposite portions of the arm, the said screw being provided at the head end thereof with a radially projecting flange or rim making contact with one surface of the arm 24, and having a nut 243 85 applied to the screw-threaded stem thereof, the said nut making contact with the opposite surface of the said arm. By means of the said screw and nut, the two members of the arm 24 may be drawn toward each other 90 to secure a proper fit of the said members against opposite portions of the cam. This means of adjustment enables all play and wear between the cam and the surfaces between which it fits to be taken up. 95

The link 25 is connected to the upper member of the arm 24 by means of a pin 244 which is carried by the said member, and eyes 245 with which the corresponding end of the link is provided. The ends of the pin 100 project at opposite sides of the portion of the arm to which the pin is applied. The eyes of the link are separated from each other a distance corresponding with the width of the said portion, which latter fits between 105 them, and the opposite ends of the pin enter the said eyes. For the reception of the pin, the said portion of the upper member is formed with a split socket 245, within which the pin is placed with its ends projecting as 110 just mentioned, the said socket having a screw 246 by means of which the socket may be contracted upon the portion of the pin within the same so as to clamp the pin securely in place. For the connection of 115 the opposite end of the link 25 with the rocker 20, the arm 200 of the said rocker is formed with an opening therethrough as indicated best in Fig. 1. This opening receives the said outer end of the link, which is enlarged and formed as a sleeve. A separate sleeve, 26, Fig. 4 occupies the bore of the 120 said outer end of the link. A separate sleeve, 26, Fig. 4 occupies the bore of the said outer end of the link. A separate sleeve, 26, Fig. 4 occupies the bore of the 125 said outer end of the link. A separate sleeve, 26, Fig. 4 occupies the bore of the said outer end of the link. A separate sleeve, 26, Fig. 4 occupies the bore of the 130

A bolt 251 is passed through sleeve 26 and also through slots 205 Figs. 2 and 3 which are formed in the opposite parallel side-portions of the arm 200, one end of the said bolt having a head formed by a projecting flange or rim which makes contact with the exterior of the arm 200 at one side thereof, and 130

the other end of the bolt being threaded and having screwed thereon a nut 252 which makes contact with the opposite side of the arm 200. By tightening up the said nut the bolt 251 is secured in its position of adjustment within the slots 205.

Washers 253, 253, are placed at the opposite ends of the sleeve 26, between the said ends and the inner sides of the side-portions 10 of the arm 200. The sleeve 26 is longer than the sleeve-like portion of the outer end of the link 25, so that the latter may turn freely upon sleeve 26 after the nut 252 and bolt 251 have been tightened up to secure 15 the said bolt in its position of adjustment. The employment of the spacing sleeve 26 between the parallel side-portions of arm 200, in conjunction with the bolt 251 with its head and nut acting against the exterior 20 sides of the said side-portions, enables the said side-portions to be clamped securely and to be held firmly against springing and twisting or torque, thereby insuring freedom from tendency to cramp or bind in connection 25 with the stud 201, by which the feed-post is connected with the upper end of arm 200.

The slots 205 in the opposite side-portions of the arm 200 of the rocker 20 permit the 30 point of pivotal connection between the link 25 and the rocker to be shifted toward or from the axis of motion of the said rocker by adjustment of the bolt 251 within the said slots, to thereby vary the length of the 35 feed-movement.

The return-stroke of the feeding devices terminates at the same point in the machine under all adjustments of the length of the feed-movement, in consequence of the slots 40 205 being formed on a curve which is concentric with the position occupied by the pin 244 at the end of the full return-stroke of the arm 24 that is produced by the action of cam 23. At the end of the return-stroke 45 of the feeding devices the needle should occupy a position in line vertically with the awl, and the needle in rising should move along such line. For the purpose of effecting adjustment in order to secure this relation 50 of the needle to the awl, I provide for delicate adjustment of the arm 24 with respect to the pivotal axis of its rocker 241. Thus, the hub 247 of the said arm is formed as a split socket which is provided with a 55 contracting screw 248. This hub-portion or socket is fitted upon a circular portion 249 of the rocker 241, which is disposed eccentrically with reference to the pivotal axis of the rocker, as will appear from Fig. 3, in 60 which the tapering socket at one end of the said rocker which receives the corresponding center-screw is indicated at 2411.

By turning the screw 248 to loosen the hub-portion or socket upon the eccentric portion 65 249, and then carefully turning the rocker

within the said hub-portion or socket, the arm may be adjusted to secure the proper position of the needle at the full end of the return stroke of the feeding devices, the arm and rocker being then clamped firmly together again by means of the contracting screw 248.

The diameters of the cam 23 are all equal, and the portions of the arm 24 between which the said cam works engage with the said cam 75 at points on the periphery thereof which are diametrically opposite each other. For these reasons, the said arm is controlled by the said cam at all times during the rotation of the cam, and held from movement in either direction save as movement is occasioned by the cam itself. The point of connection between the link 25 and the arm 24 is close to the place where the said arm is engaged with the cam. It results therefrom that the power by 80 which the arm is moved is applied practically at the said point of connection, and, conversely, that the strains which are incident to reversing the direction of movement of the rockers and feed-post at the end of each 85 stroke in either direction are applied to the arm at a point close to the place of engagement with the cam. Hence, springing of the arm in operation is obviated. The strains which are incident to operation act diamet- 90 rically of the cam and its shaft, and hence are solidly resisted by the bearings of the latter, and the machine-frame. The link 25 constitutes a direct connection between arm 24 of the vibrator and arm 200 of the rocker 20, 100

and the strains which are incident to operation act in the direction of the length of such link, and hence there is no tendency to spring the latter. The point of connection (at pin 244) of the link 25 with the arm 24 is located 105 between the axis of movement of the vibrator, of which the arm 24 forms a part, and the point of connection (at bolt 251) of the link 25 with the arm 200 of the rocker 20, so that when the vibrator is oscillated by the cam 23 110 a powerful toggle-like action results as the intermediately-located point of connection (at pin 244) is carried toward and away from the straight line which passes through the said axis and the said point of connection 115 with arm 200. For the sake of brevity I have hereinafter in certain of the claims referred to this line as the line joining centers, the centers intended being the axis and the point of connection to which reference has just been 120 made. In general, the strains which are incident to starting and moving the rockers and feed-post in either direction, and arresting the same at the end of a movement in either direction, act mainly in the direction of the 125 lengths of the link 25 and arm 24, respectively.

While I have been careful to describe fully the construction, arrangement of parts, etc., in the case of the illustrated embodiment of 130

the invention, it is to be understood that these may be varied and the principles of the invention be differently embodied without necessarily involving a departure from the spirit of the invention. A needle-feed mechanism is shown and described herein, but the invention is equally applicable to awl-feed mechanisms, and to mechanisms employing other feeding implements.

10 I claim as my invention:—

1. The combination with a feed-post, a carrier movable thereon toward and from the work, and a work-penetrating feeding implement carried by the said carrier, of a 15 vibrating arm and link constituting a toggle, means to actuate the said toggle, a swinging arm intermediate the toggle and the feed-post or head and operated by the toggle to transmit feed-strokes to the feed-post or 20 head, and means to adjust the engagement of the toggle with the swinging arm to vary the length of the feed-strokes.

2. The combination with a feed-post, and a feeding implement supported thereby of a 25 link and vibrating arm constituting an operating toggle for the said feed-post, and an actuating-cam for the said toggle, one end of said link having operative connection with the feed-post and being adjustable along a 30 curve which is concentric with the pivot of the knuckle in the initial position of the parts, the adjustment operating to vary the length of feed.

3. The combination with a feed-post, a 35 feeding implement supported thereby and a swinging arm connected with the said feed-post, of a link and vibrating arm constituting an operating toggle for the said feed-post, an actuating-cam for the said toggle, and a connection between the said link and the said swinging arm adjustable relative to the said arm along a curve which is concentric with the pivot of the knuckle in the initial position of the parts.

45 4. The combination with a feed-post, a feeding implement supported thereby and a swinging-arm connected with the said feed-post, of a link and vibrating arm constituting an operating toggle for the said feed-post, 50 actuating means for the said toggle, means to adjustably connect the said link to the said swinging-arm to enable the feed-stroke of the feed-post to be varied in length, and means to adjust the position assumed by the 55 feed-post at one terminus of the feed-stroke.

5. The combination with a feed-post, a feeding implement supported thereby and a swinging-arm connected with the said feed-post, of a link, and vibrating arm constituting an operating toggle for the said feed-post, 60 an actuating cam for the said toggle, means to adjustably connect the said link to the said swinging-arm to enable the feed-stroke of the feed-post to be varied in length, and

means to adjust the position assumed by the 65 feed-post at one terminus of the feed-stroke.

6. The combination with a feed-post, and a feeding implement supported thereby of a vibrating arm, a link joined to the said arm and in operative connection with the said 70 feed-post, actuating means for the said vibrating arm, and an adjustable eccentric-mounting for the said vibrating arm to enable the position assumed by the feed-post at one terminus of the feed-stroke to be adjusted.

7. The combination with a feed-post, and a feeding implement supported thereby of a vibrating arm, a link joined to the said arm and in operative connection with the said 80 feed-post, an actuating cam for the said vibrating arm, and means for changing the relation of the centers of the vibrating arm and the said cam to vary the position of the feeding implement at one extreme of its feeding 85 stroke.

8. The combination with a feed-post, a feeding implement supported thereby and a swinging arm connected with the said feed-post, of a vibrating arm, a link joined to the 90 said arm, an actuating cam for the said vibrating arm, means to adjustably connect the said link to the said swinging arm to enable the feed-stroke of the feed-post to be varied in length, and an adjustable eccentric-mounting for the said vibrating arm to enable the position assumed by the feed-post at 95 one terminus of the feed-stroke to be adjusted.

9. The combination with a feed-post, a 100 feeding implement supported thereby and a swinging arm connected with the said feed-post, of a vibrating arm, a link pivotally joined to the said vibrating arm, an actuating-cam for the said vibrating arm, means 105 to adjustably connect the said link to the said swinging arm along a curve which in the initial position of the parts is concentric with the point of pivotal connection between the link and vibrating arm, and an eccentric- 110 mounting for the said vibrating arm to enable the position assumed by the feed-post at one terminus of the feed-stroke to be adjusted.

10. The combination with a feed-post, or 115 head, a carrier movable thereon toward and from the work, and a work-penetrating feeding implement carried by the said carrier, of a link having one end thereof in operative connection with the said feed-post, a vibrating arm provided with a fixed yoke or fork, a cam fitting within the said fork, the other end of the said link having pivotal connection with the said vibrating arm at a point immediately adjacent the place of engagement between the said cam and the said yoke or fork and a rotating shaft on which said cam is fixed, the strains incident to operation 120 125

acting diametrically with respect to the said cam and shaft.

11. The combination with a feed-post, and a feeding-implement supported thereby of a link having one end thereof in operative connection with the said feed-post, a vibrating arm provided with a yoke or fork, a rotating cam fitting within the said fork, the other end of the said link having pivotal connection with the said vibrating arm at a point adjacent the place of engagement between the said cam and the said yoke or fork, and means to adjust the said vibrating arm lengthwise to vary the position assumed by the feed-post at one terminus of the feed-stroke.

12. In combination, in a sewing machine feed-mechanism, a feed-post or head a reciprocating member connected with the said feed-post or head and having parallel side-portions which are correspondingly slotted, a bolt extending across the said member, occupying the slots of the side-portions thereof, and adjustable in the said slots, a spacing-sleeve surrounding the said bolt between the said side-portions and against the ends of which the latter are clamped by the bolt, a link formed with a sleeve fitting the exterior of the sleeve first mentioned and moving freely thereon between the side-portions of the member aforesaid and operating means for the said link.

13. In a sewing machine, the combination with a work-penetrating feeding implement, a carrier for the said implement, and devices for operating the said carrier to cause the said implement to penetrate the material which is being operated upon, of a toggle which is operatively connected to communicate feed-movements to the carrier and implement and by toggle-action occasioning the said feed-movements with a dwell therein of definite extent while the said implement is entering and leaving the material.

14. In a sewing machine, the combination with a work-penetrating feeding implement, a carrier for the said implement, and devices for operating the said carrier to cause the said implement to penetrate the material which is being operated upon, of a toggle which is operatively combined with the said carrier to transmit feed-movements to the carrier and implement, and a cam operatively combined with the said toggle and actuating the latter to occasion the said feed-movements with a dwell therein of definite extent while the said implement is entering and leaving the material.

15. In a sewing-machine, the combination with a needle, a needle-carrier, and devices for operating the said needle-carrier to cause the said needle to penetrate the material which is being operated upon, of a toggle operatively connected to communicate feed-movements to the said needle-carrier and by

its toggle-action occasioning the said feed-movements, means to actuate the said toggle, and means to adjust the initial position of the needle-carrier and needle in the said feed-movements.

16. In a sewing-machine, the combination with a needle, a needle-carrier, and devices for operating the said needle-carrier to cause the said needle to penetrate the material which is being operated upon, of a toggle comprising a member having the outer portion thereof provided with a stationary pivotal mounting, and a second member having the transmitting portion thereof operatively connected to communicate feed-movements to the needle-carrier and needle, the said toggle by its toggle-action occasioning the said feed-movements, means to actuate the said toggle, and means to adjust the pivot of the member first-mentioned to vary the initial position of the needle-carrier and needle in the said feed-movements.

17. In a sewing-machine, the combination with a needle, a needle-carrier, and devices for operating the said needle-carrier to cause the said needle to penetrate the material which is being operated upon, of a vibrating arm, a link joined to the said arm and operatively-connected to communicate feed-movements to the said needle-carrier and needle, actuating means for the said vibrating arm, and an adjustable eccentric mounting for the said vibrating arm to enable the initial position of the needle-carrier and needle to be varied.

18. In a sewing-machine, the combination with a needle, a needle-carrier, and devices for operating the said needle-carrier to cause the said needle to penetrate the material which is being operated upon, of a vibrating arm having a fork or yoke, a link joined to the said arm and operatively connected to communicate feed-movements to the said needle-carrier and needle, a rotating actuating cam for said arm working within the fork or yoke thereof, and an adjustable eccentric mounting for the said vibrating arm to enable the initial position of the needle-carrier and needle to be varied.

19. In a sewing-machine, the combination with a needle, a needle-carrier, and devices for operating the said needle-carrier to cause the said needle to penetrate the material which is being operated upon, of a toggle having one member thereof operatively connected to communicate feed-movements to the needle-carrier and needle, and also having the motion-transmitting end of such member adjustable along a curve that is concentric with the pivot of the knuckle of the toggle in the initial position of the parts, the adjustment operating to vary the length of the feed-movement, and means for actuating the said toggle.

20. In a sewing-machine, the combination

with a needle, a needle-carrier, and devices for operating the said needle-carrier to cause the said needle to penetrate the material which is being operated upon, of a toggle comprising an arm having the outer portion thereof provided with a fixed pivotal mounting, and a link operatively connected to communicate feed-movements to the needle-carrier and needle, and also having the motion-transmitting end of such link adjustable along a curve that is concentric with the pivot of the knuckle of the toggle in the initial position of the parts, the adjustment operating to vary the length of the feed-movement, and a rotating actuating cam engaging with the said arm.

21. In a sewing-machine, the combination with a needle, a needle-carrier, and devices for operating the said needle-carrier to cause the said needle to penetrate the material which is being operated upon, of a toggle operatively connected to communicate feed-movements to the said needle-carrier and needle and by its toggle-action occasioning the said feed-movements, means to actuate the said toggle, means to adjust the initial position of the needle-carrier and needle in the said feed-movements, and means to adjust the length of the said feed-movements.

22. In a sewing-machine, the combination with a needle, a needle-carrier, and devices for operating the said needle-carrier to cause the said needle to penetrate the material which is being operated upon, of a toggle operatively connected to communicate feed-movements to the said needle-carrier and needle, comprising the vibrating arm and link, means to actuate the said arm, means to adjust the pivotal mounting of the said arm to vary the initial position of the needle-carrier and needle in the said feed-movements, and means to adjust the length of the feed-movement.

23. In a sewing-machine, the combination with a needle, a needle-carrier, and devices for operating the said needle-carrier to cause the said needle to penetrate the material which is being operated upon, of the toggle operatively connected to communicate feed-movements to the said needle-carrier and needle and comprising the vibrating arm and link, actuating means in connection with the said arm, the adjustable pivotal mounting for the said arm by which the initial position of the needle-carrier and needle in the feed movements may be varied, and means to adjust the motion-transmitting portion of the said link along a curve that is concentric with the knuckle of the toggle in the initial position of the parts to vary the length of the feed-movement.

24. In a sewing-machine, the combination with a needle, a needle-carrier, and devices for operating the said needle-carrier to cause the said needle to penetrate the material

which is being operated upon, of the toggle operatively connected to communicate feed-movements to the said needle-carrier and needle and comprising the vibrating arm having the fork or yoke and the link, the rotating actuating cam working within the said fork or yoke, the adjustable pivotal mounting for the said arm by which the initial position of the needle-carrier and needle in the feed-movements may be varied, and means to adjust the motion-transmitting portion of the said link along a curve that is concentric with the knuckle of the toggle in the initial position of the parts to vary the length of the feed-movement.

25. In a feed-mechanism for sewing-machines, the combination with a needle, its bar, a post or head having a guide in which the said bar reciprocates, and means to maintain parallelism in the different positions of the post or head, of a toggle in operative connection with the said post or head, and actuating means for said toggle effecting feed-movements of the post or head by producing movement of the knuckle of the toggle transversely with respect to the line joining centers.

26. In a feed-mechanism for sewing machines, the combination with a needle, its bar, a post or head having a guide in which the said bar reciprocates, and means to maintain parallelism in the different positions of the post or head, of a toggle comprising a link and vibrating yoke-shaped arm in operative connection with the said post or head, and a cam working in the yoke of the said arm and causing feed-movements of the post or head by producing movements of the knuckle of the toggle transversely with respect to the line joining centers.

27. In a feed-mechanism for sewing machines, the combination with a needle, its bar, a post or head having a guide in which the said bar reciprocates, and parallel links controlling the said post or head in its movements, of a toggle in operative connection with the said post or head, and actuating means for said toggle effecting feed-movements of the post or head by producing movement of the knuckle of the toggle transversely with respect to the line joining centers.

28. In a feed-mechanism for sewing machines, the combination with a needle, its bar, a post or head having a guide in which the said bar reciprocates, and parallel links controlling the said post or head in its movements, of a toggle in operative connection with the said post or head, and a cam actuating the said toggle and causing feed-movements of the post or head by producing movements of the knuckle of the toggle transversely with respect to the line joining centers.

29. In a sewing machine in which a hooked

needle and an awl are employed, the combination with said implements and the actuating connections therefor, and the feed-post, of a toggle which is operatively connected to communicate feed-movements to the feed-post and by toggle-action occasioning the said feed-movements with a dwell therein of definite extent while the feeding implement is entering and leaving 10 the work.

30. In a feed-mechanism for sewing machines, the combination with a needle, its bar, and a post or head having a guide in which the said bar reciprocates, of a toggle 15 in operative connection with the said post or head and comprising a vibrating arm and a link, a cam engaging with the said arm and occasioning feed-movements of the post or head by producing movements of the knuckle 20 of the toggle transversely with respect to the line joining centers, and means to adjust the initial position of the post or head.

31. In a feed-mechanism for sewing machines, the combination with a needle, its 25 bar, a post or head having a guide in which the said bar reciprocates longitudinally, and a swinging arm connected with the post or head, of a toggle comprising a link and vibrating arm, actuating means for said toggle 30 and means to adjustably connect the toggle to the said swinging arm to enable the feed-stroke of the post or head to be varied in length.

32. In a feed-mechanism for sewing machines, the combination with a needle, its 35 bar, a post or head having a guide in which the said bar reciprocates longitudinally, and a swinging arm connected with the said post or head, of a toggle comprising a link and 40 a vibrating arm provided with a fixed yoke, an actuating cam for said toggle working in the yoke of the said vibrating arm, and means to adjustably connect the toggle to the swinging arm to enable the feed-stroke of the 45 post or head to be varied in length.

33. In a feed-mechanism for sewing machines, the combination with a needle, its bar, and a post or head having a guide in which the said bar reciprocates, of a link and 50 a vibrating arm constituting an operating toggle for the said post or head, and actuating means for the said toggle, one end of said link having operative connection with the post or head and being adjustable along 55 a curve which is concentric with the pivot of

the knuckle in the initial position of the parts, the adjustment operating to vary the length of feed.

34. In feed-mechanism for sewing machines, the combination with a needle, its 60 bar, and a post or head having a guide in which the said bar reciprocates, of a link and vibrating arm constituting an operating toggle for the said post or head, actuating means for the said toggle, one end of said 65 link having operative connection with the post or head and being adjustable along a curve which is concentric with the pivot of the knuckle in the initial position of the parts, the adjustment operating to vary the 70 length of feed, and means to adjust the initial position of the post or head.

35. In feed-mechanism for sewing machines, the combination with a needle, its 75 bar, and a post or head having a guide in which the said bar reciprocates, of a link and vibrating arm constituting an operating toggle for the said post or head, an actuating cam engaging the said vibrating arm, one end of said link having operative connection with 80 the post or head and being adjustable along a curve which is concentric with the pivot of the knuckle in the initial position of the parts, the adjustment operating to vary 85 the length of feed and means for changing the relations of the centers of the cam and the vibrating arm to vary the position of the needle at one extreme of its feeding stroke.

36. In feed-mechanism for sewing machines, the combination with a needle, its 90 bar, and a post or head having a guide in which the said bar reciprocates, of a link and vibrating arm constituting an operating toggle for the said feed-post, an actuating 95 cam engaging the said vibrating arm, one end of said link having operative connection with the post or head and being adjustable along a curve which is concentric with the pivot of the knuckle in the initial position of 100 the parts, the adjustment operating to vary the length of feed, and means to adjust the initial position of the post or head.

In testimony whereof I affix my signature in presence of two witnesses.

FRANK W. MERRICK.
